UNITED STATES PATENT OFFICE.

ALBERT CAUCHEMONT, OF PARIS, FRANCE.

SUCTION DEVICE FOR AIR, GAS, OR SMOKE PIPES.

No. 918,962.

Specification of Letters Patent.

Patented April 20, 1909.

Application filed October 25, 1907. Serial No. 399,226.

To all whom it may concern:

Be it known that I, ALBERT CAUCHEMONT, of 17 Rue de l'Aqueduc, in the city of Paris, Republic of France, architect, have invented 5 Improvements in Suction Devices for Air, Gas, or Smoke Pipes, of which the following is a full, clear, and exact description.

The present invention has for its object a suction apparatus for air, gas or smoke pipes. 10 This apparatus which is arranged at the upper part of the exhaust pipe is characterized broadly by the fact that the outer air is unable in any case to enter the conduit surrounded by the device, whatever the direction of the wind may be.

This appliance utilizes the velocity of the external air for producing a suction effect in the discharge conduit and discharging externally, in a continuous manner, the air, gases 20 or products of combustion contained therein.

This appliance does not comprise any movable parts, it obviates the noise and grating caused by rotating appliances and unlike them it is not exposed to being rendered inoperative by being immobilized by the corrosive action of smoke, or the collection of soot and thus presenting its aperture to the wind.

The object of the invention is illustrated 30 by way of example in the accompanying drawing, in which:

Figure 1 is a vertical section of the apparatus on the line A—A of Fig. 2. Fig. 2 is a horizontal section of the same apparatus on 35 the line B—B of Fig. 1. Figs. 3 and 4 show the two parts of the apparatus separately and in perspective.

As shown in the drawing, the present apparatus comprises a pipe *a* arranged upon 40 the conduit to be ventilated and forming a continuation thereof. At its upper part this pipe is formed in such a manner as to constitute four wings *b* between each of which there is a lateral aperture *c*. These openings 45 which are directed toward the right hand or the left hand, at will, present a total cross section at least equal to that of the pipe *a*. The pipe *a* thus arranged is located inside a kind of lantern formed by a certain number of 50 appropriately bent metal strips *d* each of which presents a lateral opening *e* arranged in the opposite direction to the openings *c* in the pipe *a*.

Each of the strips *d* intersects with the adjacent strip, in such a manner that the outer air in entering at one of the openings *e* is only

able to reach the pipe *a* tangentially but not to enter it as indicated by the arrow 1 (Fig. 2.)

The strips *d* are fixed at their upper and lower parts upon two horizontal metal plates *f* and *f'* which completely close above and below, the annular space comprised between the metal strips *d* and the pipe *a*. This latter is likewise closed at its upper part, by a plate *g*.

The two parts of the apparatus are held in their relative positions by any appropriate fitting *h*.

The suction device thus constituted acts in the following manner. The air in entering 70 the apparatus at one of the openings *e* reaches the pipe *a* tangentially, as already stated. This air produces a suction effect inside this pipe and the smoke, gases or vitiated air escape through the openings *c* and pass to the 75 annular space comprised between the said pipe and the strips *d* of the lantern. Owing to the relative vacuum produced by the wind at the rear of the apparatus, the smoke or gases are drawn outside in passing through 80 the apertures *e* in the lantern.

From the foregoing it will be seen that it is impossible for any admission or discharge of air, gas or smoke to take place otherwise than laterally and that in no case can the 85 outer air enter the conduit and produce a back draft.

The arrangements described above are given by way of example only; the forms, dimensions and detail arrangements may vary 90 according to circumstances without thereby affecting the principle of the invention.

Claims:

1. A suction device for air, gas or smoke conduits, comprising a pipe closed at its upper end and having at said end hollow wings lying within the circumference of the pipe, the wings tapering downwardly and outwardly and each having a lateral opening, the combined area of the said openings being 95 approximately equal to that of the pipe, and a shell surrounding the upper end of the pipe and spaced therefrom, said shell being formed of angular strips and end plates, the strips overlapping one another with spaces there- 100 between forming openings, opening in a direction opposite to that of the openings of the wings of the pipe.

2. A suction device for air, gas or smoke conduits, comprising a pipe closed at its upper end and having at said end hollow wings lying within the circumference of the pipe 110

and each provided with a lateral opening, and a shell surrounding the upper end of said pipe and spaced therefrom, said shell being formed of angular strips and end plates, the strips overlapping one another with spaces therebetween forming openings opening in a direction opposite to that of the openings of the wings of the pipe.

3. A suction device for air, gas or smoke conduits comprising a pipe closed at its upper end and provided at said end with hollow wings having lateral openings, and a shell surrounding the upper end of the pipe and spaced therefrom, said shell being formed of strips and end plates, the strips overlapping one another with spaces therebetween forming openings opening in a direction opposite to that of the openings of the wings of the pipe.

4. A suction device for gas or smoke conduits, comprising a pipe closed at its upper end and provided at its closed end with hollow wings each provided with an opening in its side, the combined area of the openings

being approximately equal to that of the pipe, and a shell surrounding the upper end of the pipe and spaced therefrom, the shell being closed at top and bottom and having tangential openings in its periphery, opening in a direction opposite to that of the wings of the pipe.

5. A suction device for gas or smoke conduits, comprising a pipe closed at its upper end and provided at its closed end with radial hollow wings lying within the circumference of the pipe, each having an opening in its side, and a shell surrounding the pipe and spaced therefrom, the shell being closed at the top and bottom and provided with tangential openings in its periphery.

The foregoing specification of my improvements in suction devices for air, gas or smoke pipes signed by me this 14th day of October 1907.

ALBERT CAUCHEMONT.
